UNITED STATES PATENT OFFICE.

ISADORE LEIKER, OF HAYS CITY, KANSAS.

WINDOW-CURTAIN BRACKET.

Application filed May 10, 1923. Serial No. 638,021.

To all whom it may concern:

Be it known that I, ISADORE LEIKER, a citizen of the United States, residing at Hays City, in the county of Ellis and State 5 of Kansas, have invented certain new and useful Improvements in Window-Curtain Brackets, of which the following is a specification.

This invention relates to a window curtain bracket, and has for its object to provide a bracket of such class, in a manner as hereinafter set forth, whereby the same can be readily and conveniently mounted in position upon a window frame, and including 10 means for adjustably connecting with the window frame a drapery or curtain supporting rod of rigid material, and further including means for connecting with the window frame a resilient curtain supporting 15 rod.

Further objects of the invention are to provide a bracket for the purpose set forth, and in a manner as hereinafter referred to, which is simple in its construction and arrangement, strong, durable, efficient in its 20 use, conveniently connected to a window frame and comparatively inexpensive to manufacture.

With the foregoing and other objects in view, the invention consists of the novel construction, combination and arrangement of parts as hereinafter more specifically described and illustrated in the accompanying drawings, wherein is shown an embodiment 30 of the invention, but it is to be understood that changes, variations and modifications can be resorted to which come within the scope of the claims hereunto appended.

In the drawings wherein like reference 40 characters denote corresponding parts throughout the several views:

Figure 1 is a top plan view of a window curtain bracket, in accordance with this invention, and further illustrating a pair of brackets secured to a window frame and having connected therewith curtain and drapery supporting rods.

Figure 2 is a front elevation of a window curtain bracket in accordance with this invention.

Figure 3 is an end elevation of the bracket and further illustrating a drapery supporting rod connected therewith.

Referring to the drawings in detail, 1 denotes the side bars of a window frame, indicated in dotted lines, and to each of which

is adapted to be secured a pair of oppositely disposed window curtain brackets, in accordance with this invention, for the purpose of connecting, in supporting position with the 60 window frame, a resilient curtain supporting rod 2, and an adjustable rigid supporting rod for draperies formed of a pair of telescopic sections 3, 4. The drapery supporting rod is arranged outwardly with respect to 65 the curtain supporting rod.

A window curtain bracket, in accordance with this invention, comprises a body portion 5 formed of a rectangular metallic plate and which at one end is provided with a 70 rearwardly extending, right angularly disposed flange 6, carrying a plurality of barbs 7, which engage in the window frame for the purpose of connecting the body portion of the bracket in position. The plate 5, at 75 one end, centrally thereof, and opposite the terminus of the plate which is provided with the flange 6, is formed with an arm 8, disposed in a direction lengthwise with respect to the length of the plate 5, and the outer 80 face of the arm 8 is undercut as at 9, to provide a retaining hook 10, for the looped end 11, of the bar 2.

The upper portion of the plate 5 is provided with a rectangular slot 12, and the 85 bottom edge of said slot has formed integral therewith a series of spaced coupling arms, each consisting of an outwardly and upwardly inclined lower portion 13, and a vertically disposed upper portion 14, and which 90 is offset with respect to the plate, through the medium of the lower portion 13, so that the portion 14 will be arranged forwardly of the front face of the plate 5.

The coupling members provide means for 95 adjustably connecting the drapery supporting rod with the bracket, so as to provide for coupling said rod with a pair of brackets, when the length of the rod is increased or diminished, as the length of the rod can 100 be varied, due to the fact, that the rod is formed of two telescopic sections 3, 4, one adjustable lengthwise within the other.

For connecting the sections of the drapery supporting rod with a coupling member, the 105 outer end of each of the sections is provided at its top with an extended portion 15, provided with an opening 16, for the passage of the upper portion 14 of a coupling member. The edge at the outer end of each section of the drapery supporting rod is inset, as at 17, with respect to the extension or lug 110.

15. The manner in which the drapery supporting rod is connected with the bracket is clearly shown in Figures 2 and 3.

The rod 2 is formed from a closely coiled 5 spring having each end provided with a loop 11 for connection with the arm 8.

Although the flange 6 is illustrated as provided with a pair of barbs 7, which are tapered for quick insertion or engagement 10 with the window frame, yet it is to be understood that the number of barbs 7 can be increased, and preferably the barbs 7 are formed integral with the inner face of the flange 6.

15. Although the preferred embodiment of the invention is as illustrated and described, yet it is to be understood that changes in the details of construction can be had which will fall within the light of the invention as 20 claimed.

What I claim is:—

1. A window curtain bracket comprising a flat rectangular body portion positioned on edge and having its upper part for a portion 25 of its length cut away to provide a rectangular slot, and a plurality of vertically disposed arms integral with the bottom edge of said slot and providing coupling members for a curtain rod, each of said arms having the 30 upper part thereof offset to position said upper portion forwardly with respect to the front face of the body portion.

2. A window curtain bracket comprising a flat rectangular body portion positioned 35 on edge and having its upper part for a portion of its length cut away to provide a rectangular slot, and a plurality of vertically disposed arms integral with the bottom

edge of said slot and providing coupling members for a curtain rod, each of said arms having the upper part thereof offset to position said upper portion forwardly with respect to the front face of the body portion, and a lengthwise extending flat arm formed integral with the inner edge of said body portion and disposed at right angles with respect to said members and further having its outer face undercut to provide a retaining hook for a curtain supporting rod. 40 45

3. A window curtain bracket comprising a flat rectangular body portion positioned on edge and having its upper part for a portion of its length cut away to provide a rectangular slot, and a plurality of vertically disposed arms integral with the bottom edge of said slot and providing coupling members for a curtain rod, each of said arms having the upper part thereof offset to position said upper portion forwardly with respect to the front face of the body portion, 50 and a lengthwise extending flat arm formed integral with the inner edge of said body portion and disposed at right angles with respect to said members and further having its outer face undercut to provide a retaining hook for a curtain supporting rod, and a rearwardly extending right angularly disposed flange formed integral with that edge of the body portion opposite the edge from which said arm projects, said flange provided with means for securing said body portion to a support. 55 60 65 70

In testimony whereof, I affix my signature hereto.

ISADORE LEIKER.
